(57) **CLAIM**

We claim the ornamental design for a disposable sink strainer, as shown and described.

DESCRIPTION

FIG. 1 is a top, perspective view of a strainer for a sink drain; FIG. 2 is a bottom, perspective view of the strainer of FIG. 1; FIG. 3 is a top view of the strainer of FIG. 1; FIG. 4 is a bottom view of the strainer of FIG. 1; FIG. 5 is a side view of the strainer of FIG. 1; and, FIG. 6 is another side view of the strainer of FIG. 1 (with the strainer being rotated by 90-degrees relative to its position in FIG. 5).
The broken line showing is included for the purpose of illustrating portions of the article and forms no part of the claimed design.
